UNITED STATES PATENT OFFICE.

GOTTWALT SIEBER, OF PLAUEN, GERMANY.

EMBROIDERY MACHINE.

Application filed January 27, 1923. Serial No. 615,293.

To all whom it may concern:

Be it known that I, GOTTWALT SIEBER, a citizen of the German Republic, and a resident of Plauen, Saxony, Germany, have invented certain new and useful Improvements in Embroidery Machines (for which I have filed application in Germany January 26, 1922), of which the following is a specification.

10 To produce very long embroideries in which the pattern is continuously repeated, the fabric is held by two rollers attached at the ends of the machine either to the reciprocating frame members or to the stationary frame proper, a portion of the fabric being stretched out between the two rollers and extending across the machine while being provided with the embroidery. When the respective portion of the embroidery is 15 finished, it is wound upon one of the rollers and another portion of the fabric assumes its place in order to be embroidered like the preceding one or ones.

In connection with this substitution of another portion of the fabric for that just finished very great attention must be paid to making the joints between the successive portions of the embroidery practically faultless, so that it will be practically impossible to detect in the entirely finished embroidery where the singly made portions of the embroidery join one another.

Hitherto the opinion was prevailing that the fabric must be stretched out during that exchange of the consecutive portions of the fabric, or of the embroidery respectively, and for that purpose auxiliary frames have been provided which are moved together with the portion of fabric spanned over it and determine the position of the next portion of the fabric with the aid of set pins, marks, or the like. Apart from the point that the moving forward of the fabric is rendered difficult by said frames, these latter warrant by no means the nonarising of a visible joint between two consecutive portions of the embroidery as the fabric is very easily distorted by uniform spanning out and stretching, the distortions entailing grave faults at the joints as soon as the said auxiliary frames are removed.

In view of this the fabric is often times exchanged without frames of the before-mentioned kind in that it is first loosened, then pulled from the one roller to and upon the next for a sufficient length, whereafter

it is adjusted with the aid of a gauge or an equivalent implement. This procedure requires, however, much experience in order to pay due regard to all influences active 60 during the embroidering process. Besides, the procedure in question is not sufficiently accurate for the reason that the gauge is not always laid against the guide roller that serves as base line in the same manner. 65

To obviate the drawback mentioned the invention contemplates holding the fabric loose during the substitution of a portion to be embroidered for an embroidered one, i. e. during winding this latter portion upon 70 the one roller and unwinding a corresponding portion off the other roller, whereafter the new portion is spanned fast for the next embroidering operation with the aid of a mark provided at the reciprocating frame, 75 in such a manner that the newly made piece of embroidery properly joins the preceding one.

My invention is illustrated by way of example in the accompanying drawings, in 80 which Figure 1 is a front view of the movable frame of an embroidery machine, in connection with an adjusting bar thereon, Figure 2 is an illustration similar to the righthand end of Figure 1 and showing 85 a modification of the adjusting bar. Figure 3 is an illustration solely of an adjusting bar and shows another modification thereof.

The movable frame 1 is supported in 90 known manner upon rolls 2 and 3 which are capable of being lifted and lowered for the purpose of adjusting the frame 1. Near the lateral parts of the frame 1 are the fabric supporting rollers 4 and 5 which are held 95 in the usual manner so as to allow of pulling and winding the fabric from the one roller to the other. The roller 4 bears the fabric to be provided with the embroidery; the roller 5 is that receiving the embroidered 100 fabric. The piece of fabric located between the rollers is stretched out between the horizontal rails 6 and 7, of which at least the upper rail 6 may be vertically adjusted by means of screw-threaded rods 8 and winged 105 nuts, as shown in Figure 1, the main object of that adjustment being to stretch the fabric between the rails as required for the embroidery operation.

To fix the joint line for the fabric while 110 it is loose during the exchange of the consecutive portions, the movable frame is pro-

vided with a vertical bar 9 which is supported by a pivot 10 situated at the lower member of the frame; at the upper end of the bar 9 is a slot 11 through which passes 5 a threaded bolt 12 having a winged nut by which the bar 9 may be fixed in its adjusted position. It is obviously possible to turn the bar 9 a little to the left or a little to the right which is necessary if it happens that 10 the pattern sheet for the embroidery hangs, perhaps, not accurately vertically upon the pantograph board so that if the same pattern must repeatedly follow each other vertically the joint line does not extend accurately in vertical direction, but is inclined 15 to the one or the other side, as the case may be. Such faults of stretching will be overcome by the lateral adjustability of the bar 9.

20 The bar 9 is provided with a slide 13 carrying a hand or index 14 which may be moved towards the fabric in order to determine the joint between two consecutive portions of the embroidery.

25 The bar 9 is also provided with two collars 15 and 16 which form abutments for the slide 13, and, thus, for the hand 14, too; the collars fix the end positions of the slide with the hand, the end positions being those 30 given by the breadth and the position of height of the fabric. The length of the joint line need not be equal to the breadth of the embroidery; it is, in fact, sufficient to select two distinct points of the pattern to 35 determine the joint line with the aid thereof.

The novel device is used as follows:—

If a length of fabric is to be provided with a continuous pattern, the one end thereof is secured to the roller 5 and the fabric 40 portion situated between the rollers 4 and 5 is stretched out between the rails 6 and 7. The thus prepared length of fabric is embroidered in the desired manner. This having been done, and before the fabric portions 45 are exchanged, the bar 9 is so adjusted at the movable frame that the hand 14 is in the position to move along the right-hand bordering line of the embroidery made, whereafter the bar 9 is fixed in that position 50 by the bolt 12 and its nut. Then the collars 15 and 16 are so adjusted along the bar 9 that the hand 14 points to two distinct points of the embroidery; that is to say, to the one point in its one end position and to 55 the other point in its other end position.

To exchange a portion of the fabric for another portion the fabric is detached from the rails 6 and 7 so as to become loose, without the aid of an additional frame, as requisite hitherto, and the embroidered portion is then wound upon the roller 5, it being replaced by a blank portion coming from the roller 4. The latter portion of fabric is then stretched out between the rails 6 and 7, as formerly, and care is taken that

the directive points of the embroidery coincide with the point of the hand in its upper position and in its lower one as determined by the collars 15 and 16, the joint line corresponding then accurately to the path of 70 the hand point when the slide 13 is displaced along the bar 9.

The righthand rim line of the new portion of embroidery, now commenced, will then coincide accurately with the lefthand 75 rim line of the embroidery portion finished previously, as regards length, direction, and height adjustment, and it will afterwards be impossible to discover the connections 80 between the several consecutive portions of the embroidery which now forms a continuous whole in which no fault indicating a joint can be detected.

If the same pattern occurs several times above, or below, each other, i. e., in parallel 85 stripes in which the patterned portions are located in equal distances from one another, it is recommended that the bar 9 be provided with two or more hands 14 and 14', as shown by way of example in Figure 2, 90 the distance between the two hands being equal to the distance between the parallel patterns. Such a device does not only permit of ascertaining or examining the joint 95 line, but also the distance between the several directive points of the parallel embroideries located above, or below, one another upon the fabric. That is the more valuable as the fabric while being provided with the embroidery is subjected to distortions of various kinds whereby faults in the 100 joint line are caused. One of the two hands 14 and 14' will, of course, be so arranged at the slide that the distance between them can be altered.

105 Instead of providing the bar 9 with a slide with one or two or more hands, such as 14 and 14', the bar 9 may be furnished with a flat bar 13' carrying a plurality of hands 14 (Figure 3) which may be stationary or adjustable and each of which corresponds to a certain distinct point or mark of the pattern, that is to say, of the embroidery, whereby the distances between the respective points, as well as the direction 110 of the joint line, is established. It is, in this case, not even necessary to make the directive points lie all on a common line, but one or the other or several hands may project beyond the connecting line of the 115 points of the other hands and may be adjusted with respect to any desired points lying in the range of the respective projecting hands.

120 I claim:

125 1. In a device for exchanging portions of fabric upon embroidery machines in the manufacture of long embroideries in steps, the combination, with the movable frame of the embroidery machine, of an adjusting 130

bar provided at said frame, and a directive hand provided at said bar, substantially as described.

2. In a device for exchanging portions of fabric upon embroidery machines in the manufacture of long embroideries in steps, the combination, with the movable frame of the embroidery machine, of a vertical bar attached to said frame and being adapted to be adjusted thereat, and at least one directive hand provided at said bar, substantially as described.

3. In a device for exchanging portions of fabric upon embroidery machines in the manufacture of long embroideries in steps, the combination, with the movable frame of the embroidery machine, of an adjustable vertical bar adapted to be laterally moved and to be fixed in its adjusted position; at least one movable hand at said bar, and abutments between which said hand may be adjusted along the said bar, substantially as described.

4. In a device for exchanging portions

of fabric upon embroidery machines in the manufacture of long embroideries in steps, the combination, with the movable frame of the embroidery machine, of an adjustable vertical bar adapted to be laterally moved and to be fixed in its adjusted position; at least one adjustable hand at said bar; and adjustable collars provided upon the bar, substantially as described.

5. In a device for exchanging portions of fabric upon embroidery machines in the manufacture of long embroideries in steps, the combination, with the movable frame of the embroidery machine, of an adjusting bar provided at said frame, and at least one directive hand adapted to be displaced along the bar, substantially as described.

In testimony whereof I affix my signature in presence of two witnesses.

GOTTWALT SIEBER.
